FOLDING CHAIR AND TABLE SET

Henning H. Wohlk, Spokane, Wash.

Application November 21, 1949, Serial No. 128,638

3 Claims. (Cl. 155—124)

1

This invention relates to furniture, and more particularly to a folding chair and table set.

The object of the invention is to provide a combination table and folding chairs therefor, the chairs adapted to be folded into a compact unit, whereby the chairs can be positioned in an out-of-the-way position beneath the table top when the chairs are not being used.

Another object of the invention is to provide a combination table and folding chairs which can be used to comfortably support a plurality of persons seated around the table, or the chairs can be folded or collapsed and supported beneath the table top when not being used, whereby the table and chairs will occupy a minimum amount of space.

Another object of the invention is to provide a combination table and folding chairs, the chairs including suitable braces for preventing the chairs from accidentally folding during use, there being a handle on the back of each chair to facilitate the removal of the chairs from their folded positions beneath the table, and wherein the chairs can be folded and positioned beneath the table top to occupy a minimum space, as when the furniture is being stored or transported.

A further object of the invention is to provide a folding chair and table set which is extremely simple and inexpensive to manufacture.

Other objects and advantages will be apparent during the course of the following description.

In the accompanying drawings forming a part of this application, and in which like numerals are used to designate like parts throughout the same:

Figure 1 is a perspective view showing the chairs in their open position around the table and ready for use;

Figure 2 is a side elevational view of one of the chairs in its open position;

Figure 3 is a side elevational view showing one of the chairs in its collapsed or folded position;

Figure 4 is a side elevational view showing a pair of the chairs in their folded position supported beneath the table top;

Figure 5 is an enlarged side elevational view showing certain constructional details of the chair;

Figure 6 is a sectional view taken on the line 6—6 of Figure 5.

Referring in detail to the drawings, the numeral 10 designates a table which includes a horizontally-disposed base 11. Secured to the bottom of the base 11 is a plurality of blocks 12 each of which carries a glider element 13 that

2

is arranged in engagement with the floor, whereby the table 10 can be conveniently slid or moved along the floor to any desired location.

Projecting upwardly from the base 11 and secured thereto is a vertically-disposed standard or column 14, and the column 14 has a horizontally-disposed table top 15 secured to its upper end. Although the table top 15 is illustrated in the drawings as being rectangular in shape, it is to be understood that the table top 15 can have any desired shape, as for example, the table top may be circular in shape. Arranged adjacent the lower end of the standard 14 and secured thereto is a plurality of spaced body members 16 which define therebetween guideways 17 for a purpose to be later described.

The persons seated around the table 10 are adapted to be supported on folding chairs 18. In Figure 1, four of the chairs 18 are shown, but more or less of the chairs can be used if desired. As each of the chairs 18 has the same construction, only one will be described in detail. Each chair 18 comprises a back member 19 that has a handle 20 secured thereto. The handle 20 is adapted to be gripped in the user's hand so as to facilitate the removal of the chair 18 from beneath the table top 15, where the chairs are to be used.

Each chair 18 includes a seat 21 that is hingedly connected to the back member 19 by a hinge 22, the seat 21 serving to support a person when the chair is in its open position. A hinge 23 pivotally or hingedly connects a leg extension 24 to the lower end of the back member 19. Arranged adjacent the front end of the seat 21 and secured thereto is a block 25, and a hinge 27 hingedly or pivotally connects the upper end of a front leg 26 to the block 25.

Each of the front legs 26 includes a pair of vertically-disposed, spaced members 28 and extending between the pair of members 28 is a pair of horizontally-disposed strips 29 and 30. The strips 29 and 30 coat with the members 28 to define a cut-out or recess 31 for a purpose to be later described.

Each of the chairs 18 further includes an arcuate arm 32 that has one end pivotally connected to the seat 21, while the other end of the arm 32 is pivotally connected to the leg extension 24 by a hinge 33, the hinge connection between the upper end of the arm 32 and the seat 21 being designated by the numeral 34. The arm 32 serves to maintain the leg extension 24 in its open or extended position when the chair is being used. Secured to the bottom of the seat 21 by suit-

able securing elements, such as screws 36, is a slide bracket 35 which has an L-shape. The bracket 35 is provided with an elongated slot 37 which terminates in a transverse portion 38. A pin 39 slidably and hingedly connects one end of a first brace 40 to the bracket 35, the pin 39 extending through the slot 37. A pin 41 pivotally connects the other end of the first brace 40 to the back member 19. The pin 39 also slidably and pivotally connects one end of a second brace 42 to the slide bracket 35, while a hinge 43 pivotally connects the other end of the second brace 42 to the front leg 26 of the chair 18.

When the chair is in its open position and being used, the pin 39 is positioned in the transverse portion 38 of the slot 37, whereby the front leg 26 and the seat 21 will be maintained safely in their extended or open positions, so that the chair will not accidentally collapse or fold up during use. A horizontally-disposed support member 44 is secured to the back member 19 of the chair, and the support member 44 helps to support the seat 21 when the chair is being used.

For maintaining the chairs 18 in alignment when the chairs are open and being used, there is provided for each chair a hinged lever 45. Thus, each lever 45 comprises a first section 46 that is hingedly connected to the leg extension 24 by a hinge 47. A second section 48 is hingedly connected to the first section 46 by a hinge 49, and the free end of the second section 48 is adapted to be positioned in the guideway 17. When the chairs are not being used, the section 48 is folded against the section 46 and these folded sections are inserted through the cut-out 31 in the front leg 26, whereby the chair will be maintained in its folded or collapsed position, as shown in Figures 3 and 4.

When the furniture of the present invention is being used, the parts are in the positions shown in Figure 1. Thus, the chairs 18 serve to support persons thereon and the ends of the sections 48 are seated in the guideways 17 so as to maintain the chairs 18 in alignment, whereby the persons seated around the table 10 can use the table top 15 for any desired purpose. It is to be noted that the pin 39 is positioned in the transverse portion 38 of the slot 37 when the chairs are being used, so that the seat 21 and the front leg 26 will not accidentally fold. Also, the arm 32 serves to maintain the leg extension 24 in its open position. When the chairs are not being used, the chairs 18 can be readily folded and supported on the base 11 beneath the table top 15, whereby the furniture will occupy a minimum amount of space, as when the furniture is to be stored or transported. To fold the chairs, the pin 39 is moved downwardly out of the transverse portion 38 of the slot 37, and the seat 21 is pivoted about the hinge 22, so that it occupies or assumes a position contiguous to the back member 19. Also, the front leg 26 is pivoted about the hinge 27 to a position contiguous to the seat 21, and further, the lever 45 is folded about the hinge 49 and the sections 46 and 48 are inserted through the cut-outs 31 in the front leg 26, whereby the parts of the chair will be maintained in their folded position, so that accidental opening of the chair will be prevented. After the chairs 18 have been collapsed or folded, the parts are in the positions shown in Figures 3 and 4, and it will be seen that the leg-extension 24 has also been pivoted about the hinge 23. Then, the folded chairs 18 can be readily supported on the base 11 beneath the table top 15,

so that the entire table-and-chair set will occupy a minimum amount of space. When the chairs are to be used, the user need only grip the handle 20 and remove the chairs from the positions of Figure 4, and by reversing the previously-described procedure, the parts of the chair can be moved to the position shown in Figures 1 and 2, whereby the chairs are ready for normal use.

The furniture may be made of any suitable material, such as wood, and any number of chairs can be used as desired. The furniture is attractive and is especially suitable for use in small apartments or other places where space is at a premium, the furniture set being suitable for indoor or outdoor use.

What is claimed is:

1. In combination, a table including a horizontally-disposed base, a plurality of spaced glide blocks secured to the bottom of said base for supporting the latter, a vertically-disposed standard projecting upwardly from said base and secured thereto, a horizontally-disposed top supported on the upper end of said standard, a plurality of chairs for supporting persons thereon when in their open positions, said chairs adapted to be folded when not being used and supported on said base, each of said chairs comprising a back member, a seat having one end hingedly connected to said back member intermediate the ends thereof, a leg extension hingedly connected to the lower end of said back member, a front leg having its upper end hingedly connected to the other end of said seat, a slide bracket secured to the lower surface of said seat, a first brace having one end pivotally connected to said back member and its other end slidably connected to said bracket, a second brace having one end pivotally connected to said front leg and its other end slidably connected to said bracket, said first and second braces serving to prevent accidental folding of said chair, and an arcuate arm having one end pivotally connected to said seat and its other end pivotally connected to said leg extension for maintaining said leg extension in extended position when the chair is being used.

2. The apparatus as described in claim 1, and further including a lever embodying a pair of sections pivotally connected together and hingedly connected to said leg extension, and a plurality of spaced body members secured to the lower end of said standard and defining guideways therebetween for receiving said levers when the chairs are in their open positions.

3. In combination, a table including a base, a plurality of spaced slide blocks secured to said base for supporting the latter, a standard projecting upwardly from said base and secured thereto, a top supported on the upper end of said standard, a plurality of chairs for supporting persons thereon when in their open positions, said chairs adapted to be folded when not being used and supported on said base, each of said chairs comprising a back member, a seat having one end hingedly connected to said back member intermediate the ends thereof, a leg extension hingedly connected to the lower end of said back member, a front leg hingedly connected to the other end of said seat, a slide bracket secured to the lower surface of said seat, a first brace having one end pivotally connected to said back member and the other end slidably connected to said bracket, a second brace having one end pivotally connected to said front leg and the other end slidably connected to said bracket, said first and second braces serving to prevent accidental

folding of said chairs, and an arm having one end pivotally connected to said seat and the other end pivotally connected to said leg extension for maintaining said leg extension in extended position when the chair is being used.
